UNITED STATES PATENT OFFICE.

JOHN A. ZUBLIN, OF LOS ANGELES, CALIFORNIA.

IMPACT DRILL.

Application filed August 9, 1922. Serial No. 580,645.

This invention relates to impact drills, and is particularly directed to earth boring drills adapted for use in connection with the standard type of impact well drilling equipment.

It is an object of the invention to provide an impact drill having a depending transverse cutter blade and two diagonally opposite side wings or shoulders on opposite sides of the blade dressed out to form reaming cutters, and in which the major portion of the drilling is accomplished by the blade which breaks or splits the material from the bottom of the well bore, the reaming cutters functioning to produce a round straight hole.

Another object is to provide a drill of the above character in which the under surfaces of the shoulders act as impact surfaces serving to crush the loosened material and mix soft material with circulation water in the well bore.

A further object resides in the angling of the under surfaces of the shoulders upwardly from the base of the blade whereby by reason of the disposition of the shoulders on opposite sides of the vertical axis of the drill combined with their being angled in opposite directions, the action of said shoulders against the circulation water and against the earth will effect a partial rotation of the drill during each downward stroke so that the cutter blade will strike the bottom of the hole at substantially regular circular intervals, this action contributing to the production of a straight round bore.

Another object is to provide an impact drill having a depending transverse cutter blade and two diagonally opposite side wings or shoulders on opposite sides of said blade dressed out to form concentric reaming cutters, whereby the blade penetrates the formation without shattering the surrounding part of the ground thereby avoiding caving of the walls in unconsolidated formations, the reaming cutters subsequently reaming the bore to full diameter.

A further object is to provide a drill as above referred to in which the blade breaks or loosens the material from the bottom of the bore, and in which the shoulders are dressed backwards and upwards in a manner similar to propeller wings and function to crush the material and to force the loosened material away from the shoulders, partly into flutes in the drill shank, and

partly into the walls of the bore when working in soft or unconsolidated formation.

Various other objects and advantages will be more fully apparent from the following description of the accompanying drawings, which form a part of this disclosure, and which illustrate a preferred form of embodiment of the invention.

Of the drawings:

Figure 1 is an elevation of my improved type of drill.

Fig. 2 is a plan section on line 2-2 of Fig. 1.

Fig. 3 is a bottom plan view. 70

Fig. 4 is an elevation of the lower portion of the drill, shown in a well bore and looking in the direction of the arrow 4 in Fig. 2.

Fig. 5 is a similar elevation looking in the direction of the arrow 5 in Fig. 2. 75

Fig. 6 is a perspective view of a section of drill stock from which the drill is formed.

Fig. 7 is a perspective view illustrating the first step in the formation of the drill.

Fig. 8 is a perspective view of the lower end of the completed drill. 80

Fig. 9 is a bottom plan view of a piece of standard drill stock illustrating the first step in the formation of my improved drill from such stock. 85

Fig. 10 is a view similar to Fig. 1, illustrating a slight modification of the form of the transverse cutter blade.

Fig. 11 is an elevation of a standard type of bevel bit or drill, in a well bore. 90

Fig. 12 is an elevation of a standard type of flat bottom bit or drill, in a well bore.

Fig. 13 is a diagrammatic illustration of the packing effect of a standard flat bottom bit. 95

In the well known cable drilling system now in general use, two standard types of drills or bits are generally employed, namely, a beveled bit as shown in Fig. 11 and having its lower end dressed to form two inclined transverse planes 1 forming a central cutting edge 2, and a flat bottom bit as shown in Fig. 12 and in which the cutting and reaming edges 3 are of the full diameter of the well bore. 100

The beveled bit shown in Fig. 11 has no crushing planes by which the boulders or larger pieces of hard material will be crushed and such material, indicated at *a*, contacting with one or the other of the beveled surfaces 1 will tend to deflect the drill sidewise, as indicated by the arrow *b*, with 110

the result that a crooked bore will be produced. Further, as such a drill has no rotary movement excepting such as can be effected from the surface by manipulation of 5 the drill cable, it often happens that the drill will "key-seat" in the well bore, that is, by striking the same spot at each downward stroke the drill will form a hole of the exact shape of the drill instead of forming 10 a round hole and after a few strokes will become stuck in the formation.

With a flat bottom bit of the form shown in Fig. 12, and working in unconsolidated formation, the flat bottom compresses and 15 packs the formation in the area 4 rendering it more difficult to break up, and further by continual pounding against such packed formation, tends to shatter the surrounding formation making it more liable to cave into 20 the hole and bury the whole string of tools. This action produces a bore having a hard packed bottom and relatively loose side walls, as diagrammatically illustrated in Fig. 13 which is the reverse of an ideal condition 25 of soft bottom which the drill has to break up and hard sides to prevent caving. The entire work of cutting and reaming is accomplished entirely by the cutting edges 3 which must break the material in a corner in which one-quarter or 90° of the circle 30 is open and three-quarters or 270° of the circle is of solid material, as indicated in Fig. 12, this condition requiring that the bit has to break the material at a point offering 35 the greatest resistance. Thus, the entire drilling strains are localized at the two cutting edges with the result that such a bit rapidly wears to such an extent as to require frequent removal for redressing and 40 resharpening.

Summing up the deficiencies and objectional features incident to the use of such standard drilling tools, the beveled bit of Fig. 11 is very susceptible of being laterally deflected and cannot be relied upon to bore a straight hole, and further is very susceptible of becoming "key-seated" in the well bore. The flat bottom bit of Fig. 12, by first packing the formation which it must 45 subsequently break up, creates a condition adding to the work which the drill must perform, and also creates a condition by reason of which the bore, in loose formations, is very liable to cave in. Even under favorable conditions the drill speed of the flat bottom bit is relatively low, and while the drilling speed of the beveled bit is considerably greater, its tendency to bore crooked holes quite offsets any advantage in actual 50 drilling speed. While the flat bottom bit causes a very effective mixing of the loosened material with the water, due to the vacuum influence created beneath the large flat surface during the up-stroke and the 55 abrupt displacement of water by said flat

surface on the down stroke, neither of said standard bits positively direct the material up into the flutes, and for this reason only such material as happens to find its way into the flutes will be carried up the drill shank 70 by the water.

With the above in mind I have invented a new type of impact drill which while retaining the mixing effect of the flat bottom bit, has none of the above named objectionable features, and which by actual field tests show an increase of drilling speed of not less than one hundred percent. 75

The drill of the present invention may be formed from the standard type of drill stock shown in Fig. 9, or from drill stock of the shape shown in Fig. 6, the only difference being that the special type of drill stock eliminates corners and edges which are unnecessary and which complicate slightly the work of forming and dressing the bit. 80

In Fig. 6, I have illustrated the preferred type of drill stock from which my improved drill is preferably formed, and which has opposite vertical edge surfaces 5, adjacent angled corner surfaces 6, and opposed longitudinal flutes 7, with the walls of the flutes angled outwardly to meet the edges of the corner surfaces 6. 95

In the drill as shown in Fig. 1, the upper portion of the shank 8 is formed to provide the usual type of neck 9 having flat surfaces 10 for engagement by suitable wrenches or other tools, and a screw-threaded tapered pin 11 adapting the tool for attachment to the tool string. 100

A preferred manner of forming the drill from the type of drill stock shown in Fig. 6, consists of first cutting back the stock 105 along dotted lines 12 connecting two of the opposed corner surfaces 6, down to the dotted lines 13, preferably by means of an acetylene torch, thus forming a diagonal central web 14 and diagonally opposite shoulders 15 on opposite sides of said web, as shown in Fig. 7. 110

With the drill stock cut back in this manner, the drill is forged or otherwise formed to the shape shown in Fig. 8, the web 14 being dressed to form a transverse cutting blade 16 extending downwardly from the shank 8 between the flutes 7 and diagonally disposed relative to the disposition of the flutes with the sides of the blade tapered and beveled to a chisel cutting edge. 115

The respective shoulders 15 are angled upwardly from the base of the cutting blade 16 to their outer points 17, and are dressed out to circular cutting edges 18 coincident to the full diameter of the well bore, these shoulders functioning as impact shoulders to crush the loosened material and as reaming cutters for reaming the well bore to size. 120 125 130 135 140 145 150

With the impact surfaces 15 angled upwardly and outwardly from the base of the blade 16 to the points 17, the cutting edges 18 will be angled circularly from their forward points 20 backwardly and upwardly to the respective rearward points 17, the terms forward and rearward as used being coincident to the directions of rotation of the drill, and as the respective shoulders are on opposite sides of the vertical axis of the drill and are angled in opposite directions from the blade 16, it will be understood that upon each down-stroke, the shoulders will have a screw-like action upon the circulation 10 water and upon the formation during reaming, effecting a partial rotation of the drill in the direction of the arrows 21 in the several views.

In some instances it may be desirable to 20 form the cutting blade of sufficient width to span the entire diameter of the well bore, whereby the blade does substantially all the work of boring excepting for the work of truing the bore which is accomplished by 25 the reaming cutters. In such instances the blade 16 may be dressed outwardly to the full diameter as shown in Fig. 10.

In forming a drill from standard drill stock of the shape shown in Fig. 9, the web 30 14^a may be disposed as shown, leaving corners 22 which will be dressed back, or which may be left without such dressing back as they will have no appreciable effect on the operation of the drill.

35 In a drilling operation, the transverse cutting blade 16 cuts or loosens the formation ahead of the reaming cutters thereby assuming a major portion of the work and the drill by its turning movements causes said 40 blade to strike the bottom of the hole at regular circularly spaced intervals thereby preventing "key-seating" and permitting the circulation water to freely enter each cut. The impact shoulders 15 crush the pieces of 45 material cut by the blade, forcing such cuttings into the flutes 7, as indicated by the arrows 23, and in loose or unconsolidated formation partly back into the wall of the bore, as indicated by the arrows 24, thereby 50 reinforcing and packing such wall to reduce danger of caving thereof. This crushing action does not pack the material at the bottom of the bore, as do the standard types of bits, for the reason that this crushing action 55 centers at points 25 which are outwardly from the side walls of the bore, as illustrated in Fig. 5.

When the reaming shoulders strike the formation in a reaming operation a positive 60 rotation of the drill is effected by reason of said shoulders being respectively on opposite sides of the vertical axis of the drill and by reason of their being respectively angled upwardly and circumferentially in opposite 65 directions in the form of a screw-thread.

The work of redressing the drill consists of driving back the shoulders sufficient to restore the transverse blade to its original length, sharpening said blade, and redressing the reaming edges of the shoulders to 70 size. This can be accomplished in the field or in a shop, as desired.

In the actual operation of my bit, the cutting blade 16 is of sufficient length to enter the material at the bottom of the hole and 75 to penetrate therein before the impact shoulders 15 strike this material. As a result, the bit has a double cutting action. The cutting blade enters the formation without rotation and after it has penetrated sufficiently 80 to bring the impact shoulders into contact with the material at the bottom of the hole, it is given a marked twist. This twist is due to the impact shoulders being so disposed that both of them tend to twist the bit in 85 the same direction as they wedge against the bottom of the hole and because their maximum action is exerted at the greatest possible radius, that is, at the periphery of the 90 hole.

This double cutting action is most important as the cleavage planes of the formations ordinarily penetrated are roughly horizontal, or at a small angle with the horizontal. The twisting action, therefore, tends to shear off flakes of material along these cleavage planes and, since the materials drilled have, ordinarily, very little shearage strength along these planes, twisting action is most 95 effective.

To be effective, however, the bit must be made, as shown, in such a manner that the cutting blade penetrates the material, without twisting, sufficiently to get a twisting grip on the material before impact shoulders 100 strike bottom and supply the twist.

My bit cuts, as do all impact bits, by virtue of the energy stored therein at the moment of impact. A portion of this energy is applied to forcing the cutting blade into the formation to be cut, a portion is applied to reaming the hole by the impact shoulders; and a portion is converted into rotary motion for the purpose of turning the cutting blade and thereby shearing off material from 110 the bottom of the hole.

So far as I am now aware, I am the first to provide a bit with a cutting blade which is first driven into the material to be drilled and then twisted to shear off flakes of this material. I am also the first to cause a freely suspended and reciprocated bit to cut both by impact and rotation, using the stored energy in the moving bit for both purposes.

While the drill as illustrated and described herein is well adapted to fulfill the objects primarily stated, it is to be understood that I do not wish to limit the invention to the embodiment herein disclosed, for it is susceptible of embodiment in various other 120 125 130

forms, all coming within the scope of the following claims.

I claim:

1. An impact drill adapted to rotate during its impact stroke and having a shank provided with flutes on opposite sides thereof and a transverse cutting blade between the flutes and extending downwardly from the shank, the lower surface of the shank forming opposed impact surfaces on opposite sides of the blade and the blade being diagonally disposed relative to the disposition of the flutes so that approximately the entire area of each impact surface is positioned to one side of the adjacent flute, each impact surface being extended rearwardly relative to the direction of rotation and angled upwardly from the base of the blade.
2. An impact drill adapted to rotate during its impact stroke and having a shank and a transverse cutter blade extending downwardly therefrom, the shank at the base of the blade having two diagonally opposite side wings or shoulders on opposite sides of the blade to provide impact crushing surfaces angled upwardly from the base of the blade with the outer edges of the shoulders being dressed out concentric to the vertical axis of the shank to form reaming cutters.
3. An impact drill adapted to rotate during its impact stroke and having a shank and a transverse cutter blade extending downwardly therefrom, the shank having two diagonally opposite side wings or shoulders extending rearwardly relative to the direction of rotation and disposed on opposite sides of the blade to provide crushing impact surfaces angled upwardly from the base of said blade with their outer edges angled upwardly and circumferentially and dressed out concentric to the vertical axis of the shank to form reaming cutters.
4. An impact drill including a shank provided with a relatively thin cutter blade having a transverse cutting edge and opposite side walls, the lower end of the shank

having two diametrically opposite impact shoulders on opposite sides of the blade and diagonally disposed relative to the plane of the blade, each shoulder extending outwardly from the base of the side wall of the blade.

5. A bit for drilling deep wells, said bit operating by falling through a distance in a well and comprising: a cutting blade having sides forming equal angles with the central plane of the blade; and impact shoulders situated on opposite sides of said plane and on opposite sides of a plane at right angles thereto and passing through the axis of said bit, said impact shoulders being so inclined that they cooperate to rotate the bit.

6. A bit for drilling deep wells, said bit operating by falling through a distance in a well and comprising: a cutting blade adapted to be driven into the material to be cut without rotation and so formed as to exert a twisting grip on said material when so driven; impact shoulders formed on said bit, said impact shoulders being situated on opposite sides of said cutting blade and so shaped and situated as to impart a twisting moment to said bit as they are forced into said material; and cutting edges formed at the outer parts of said impact shoulders.

7. A bit for drilling deep wells, said bit operating by falling through a distance in a well and comprising: a cutting blade adapted to be driven into the material to be cut without rotation and so formed as to exert a twisting grip on said material when so driven; impact shoulders formed on said bit, said impact shoulders being situated on opposite sides of said cutting blade and so shaped and situated as to impart a twisting moment to said bit as they are forced into said material; and arcuated cutting edges formed at the outer parts of said shoulders.

Signed at Los Angeles, California, this 3d day of August 1922.

JOHN A. ZUBLIN.
